Primary Examiner — Paula Greene(74) *Attorney, Agent, or Firm* — Karen B. Tripp(57) **CLAIM**

The ornamental design for casket lid cover, as shown and described.

DESCRIPTION

FIG. 1 is a perspective view of a casket lid cover showing my new design.

FIG. 2 is a side view of the casket lid of FIG. 1, showing the casket lid in a closed position on a casket.

FIG. 3 is the opposing side view of the casket lid of FIG. 2.

FIG. 4 is an end view of the casket lid of FIG. 1.

FIG. 5 is the opposing end view of the casket lid of FIG. 4.

FIG. 6 is a top view of the casket lid of FIG. 1; and, FIG. 7 is a bottom view of a casket having the casket lid of FIG. 1.

The broken lines depict environment for the purpose of illustration that forms no part of the claimed design.

1 Claim, 6 Drawing Sheets(56)
